E. Quimby,

Horseshoe Beveler.

No. 97,811.

Patented Dec. 14, 1869.

United States Patent Office.

EPHRAIM QUINBY, OF COMSTOCK, MICHIGAN.

Letters Patent No. 97,811, dated December 14, 1869; antedated December 1, 1869.

IMPROVED HORSESHOE-BEVELLER.

The Schedule referred to in these Letters Patent and making part of the same.

To all whom it may concern:

Be it known that I, EPHRAIM QUINBY, of Comstock, in the county of Kalamazoo, and State of Michigan, have invented a new and improved "Horseshoe-Beveler;" and I do hereby declare that the following is a full and exact description thereof, reference being had to the accompanying drawings, and to the letters of reference marked thereon, making a part of this specification.

The nature of my invention consists in providing a simple device upon which horseshoes are shaped, in such a manner, after being in other respects completed, that the heel of the web of the shoe, from the last nail-hole to the calk, is formed with a bevel inclining outward, so that when fitted to the foot of the horse, the tendency in process of wearing is to expand the hoof rather than contract it, thereby remedying and avoiding the evils of "hoof-bound" and contracted feet in horses.

To enable others skilled in the art to make and use my invention, I will proceed to describe its construction and operation.

I construct my beveler out of cast-iron, resembling somewhat in shape the bottom part of the hoof of a horse, as shown in the accompanying drawings at A B, and sufficiently strong and thick to perform the functions required in operating.

In and about the centre I raise a projection, as shown at P, in the drawings, around which the shoe fits, after being otherwise finished, in the operation of shaping it, as hereinafter mentioned, and intended to aid in keeping the shoe in its proper position.

Around this projection, as above described, I construct the rim of the beveler; about the width of the web of the shoe, as shown at a a', &c., in the drawings; and at the back part or heel, as above mentioned, I construct with a bevel inclining outward, and of greater or less slope or inclination, as the case re-

quires, usually, however, but slightly, as shown at b b', &c., in the drawings.

This bevel is made to extend from about the last nail-hole in the shoe to the calk, and its purpose is so to form the shoe that, in wearing, the hoof of the horse at the heel will be permitted to spread and expand rather than contract, as above mentioned.

At the ends of this bevelled rim, as above described, I cut out nooks, as shown at c c', &c., in the drawings, the object and purpose of which is to allow the calks of the shoe to drop into in the operation of shaping the bevel, after the shoe is otherwise finished, and so as to allow of a more perfect bevel-shape at the heel of the shoe than would be effected were not the calks placed in the nooks above described.

At a point in the centre of the back or bottom side of my beveler, I construct out of wrought-iron a square pin the desired length, as shown at H, in the drawings, for the purpose of holding the device on the anvil in operating it, as hereinafter mentioned.

I operate my "horseshoe-beveler" in the following manner:

I place it on the anvil, the square pin above described fitting in the handy-hole, securely holding it. Then the shoe being otherwise done, I place it upon the former while hot, being held thereon with tongs, the calks fitting into the nooks above described, and the bevel-shape is given by distinct blows of the hammer, on each side, until the desired shape is produced.

What I claim as my invention, and desire to secure by Letters Patent, is—

1. Constructing a horseshoe—"former" with a bevelled surface at and near the heel portion, as and for the purposes specified.

2. The improved former herein described.

Witnesses: EPHRAIM QUINBY.

O. T. TUTHILL,
WILLIAM BAKER.
